BUS-BAR

Richard W. Shoemaker, Woodbury, Conn., assignor to The Chase Companies, Incorporated, Waterbury, Conn., a corporation

Application May 29, 1935, Serial No. 24,061

2 Claims. (Cl. 173—13)

This invention relates to an improvement in bus-bars, and particularly to bus-bars of tubular form in cross-section.

In alternating-current bus-systems, the walls of the tubular bus-bars are subjected to very high collapsing strains, especially under short-circuit conditions. In a 60-cycle alternating-current system, the collapsing force would be of a pulsating or vibratory character exerted 120 times per second. Composite bus-bars, as generally heretofore made, have required that their component parts be securely clamped together at short intervals, but, owing to the mechanical vibrating effect of the current passing therethrough, such fittings have been susceptible to loosening under the vibrating force which under some conditions may rise as high as 5,000 lbs. per linear foot of bus-bar.

One of the objects of the present invention is to provide a ventilated tubular bus-bar which will be substantially proof against the disintegrating effects of the vibratory stresses set up by heavy currents flowing therethrough.

A further object is to provide a ventilated tubular bus-bar having superior rigidity.

Another object is to provide a tubular bus-bar in which the character of the ventilating-means is such as to have a minimum effect upon the conductivity of the bus-bar.

A still further object of the present invention is to provide an arrangement whereby the bus-bar will be effectively cooled by air-currents without unduly reducing its conductivity or its mechanical strength.

With the above and other objects in view, as will appear to those skilled in the art from the following, considered in conjunction with the accompanying drawings and appended claims, the present invention includes all features within the range of the said claims.

In the accompanying drawings:

Fig. 1 is a broken plan view of a portion of a bus-system composed of bus-bars embodying the present invention;

Fig. 2 is a broken perspective view of one form which a tubular integral ventilated bus-bar may assume in accordance with the present invention;

Fig. 3 is a longitudinal sectional view thereof, taken on the line 3—3 of Fig. 2;

Fig. 4 is a transverse sectional view taken on the line 4—4 of Fig. 2;

Fig. 5 is a similar view taken on the line 5—5 of Fig. 2;

Fig. 6 is a broken perspective view of an inte-

gral tubular bus-bar having slot-like ventilating-ports; and

Fig. 7 is a transverse sectional view taken on the line 11—11 of Fig. 10.

The particular bus-bar 20 illustrated in Figs. 1 to 5 inclusive of the accompanying drawings is of rectangular form in cross-section and includes a flat top-wall 21, a flat bottom-wall 22 and complementary flat side-walls 23 and 24, all of which are formed integrally. The bus-bar is preferably of drawn copper or other metal of high electroconductivity.

Adjacent its point of juncture with the integral side-wall 24, the top-wall 21 of the bus-bar is formed with a longitudinal series of spaced-apart air-egress ports 25, each of which is separated from its neighbor by an integral web 25a completing the one-piece perimeter of the said ports.

The bus-bar is also formed in its bottom-wall 22 with a longitudinally-extending series of air-ingress ports 26 which are located longitudinally intermediate the air-egress ports 25 and also laterally displaced with respect to the latter, so as to be located adjacent the junction point of the said bottom-wall 22 with its integral side-wall 23. Like the ports 25, the air-ingress ports 26 are separated from each other by integral webs 26a, the ends of which latter complete the integral walls of the said ports 26.

As the bus-bar becomes heated due to the passage of an electric current therethrough, air will be drawn, by convection, inwardly through the air-ingress ports 26 in the bottom-wall 22 and will flow both longitudinally and laterally, and will ultimately exit upwardly through the air-egress ports 25 in the top-wall 21, as indicated particularly well in Figs. 3 to 5 inclusive.

By the staggered relationship of the air-ingress ports 26 and the air-egress ports 25, a maximum cooling effect is obtained with a minimum amount of cutting away of the metal, inasmuch as the air entering through the ingress-ports 26 is forced to travel both longitudinally and laterally before it can escape from the interior of the bus-bar, thus wiping, so to speak, a maximum amount of the internal surface of the tube.

Furthermore, by staggering the egress-ports 25 and the ingress-ports 26 longitudinally with respect to each other, the conductivity of the bus-bar is cut down to a lesser extent than would be the case were the said ports located transversely in line. In other words, despite the fact that the tube is perforated both top and bottom, the conductivity of the tube at any given transverse

point is cut down only by the amount of metal removed by the production of but one port. The mechanical strength of the bus-bar is also least affected by the staggering of the ports, as described.

When heavy alternating currents are flowing through the bus-bar, the webs 25^a and 26^a effectively prevent relative movement between the metal on the respective opposite sides of the ports 25 and 26, thus obviating one of the objections inherent in prior bus-bar structures.

In Figs. 6 and 7 is shown an integral drawn tubular bus-bar 34, also of rectangular form in cross-section and including a top-wall 35, a bottom-wall 36 and complementary side-walls 37 and 38, all formed integrally with each other.

Instead of perforating the top- and bottom-walls, the bus-bar 34 is perforated in its side-walls in staggered relationship. Thus, the side-wall 37 is provided with a series of longitudinally-extending slot-like air-egress ports 39, located in the said side-wall adjacent the point of the junction of the latter with the top-wall 35 and having interposed between them integral webs 39^a. At a materially-lower level than the level of the ports 39, the wall 38 of the bus-bar is formed with a series of longitudinally-extending slot-like air-ingress ports 40, preferably located in the said side-wall at a point adjacent the junction of the latter with the integral bottom-wall 36 and spaced from each other by integral webs 40^a.

By reference to Fig. 7 in particular, it will be seen that the egress-ports 39 and the ingress-ports 40, by virtue of their vertically-staggered relationship, cause air entering the said ingress-ports 40 to wipe against a large area of the interior surface of the tube before escaping through the egress-ports 39.

It will be noted that while a given pair of the ports 39 and 40 are vertically staggered in displaced relationship with respect to each other, they are substantially laterally in line, and for this reason it is preferred to secure the necessary port area by making the said ports of slot-like form extending longitudinally of the bus-bar, so that the reduction in cross-sectional area of the bus-bar at a given point is kept at a minimum.

All of the bus-bars herein illustrated are extremely economical of installation and effective in operation, owing largely to the integral character of the structure. Thus, especially under short-circuit conditions, the pulsating collapsing forces (which are applied and released 120 times per second in a 60-cycle system) have no effect in loosening one wall with respect to another. Furthermore, by the integral character of the webs between any given pair of ports of the same series, not only is superior mechanical strength obtained, but clamping-fittings, usually required in great numbers, may largely, if not entirely, be dispensed with.

It will be obvious, without further illustration, that the various ports may be of various shapes and spacings. Bus-bars of rectangular form in cross-section are much to be preferred in present practice, for the reason that they provide suitably-located flat faces against which connecting-plates for branches (both vertical and horizontal) may be secured.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A one-piece wrought tubular bus-bar designed and adapted for current-carrying bus-systems and composed of high electro-conductive metal and of rectangular form in cross-section and having substantially-flat integral top-, bottom- and side-walls; the said rectangular bus-bar being formed in a lower wall-portion with a longitudinal series of spaced-apart air-ingress ports, and also formed in an upper wall-portion with a longitudinal series of spaced-apart air-egress ports, the individual air-ingress ports being separated from others of the series thereof by webs of metal formed integrally with the metal of the rectangular bus-bar, and the individual air-egress ports of the series thereof being also separated from companion ports by integral webs; certain of the said series of air-ingress ports being located laterally intermediate the longitudinal center-line of the upper-wall portion of the bus-bar and a side-edge of such wall portion and laterally staggered with respect to certain of the said series of air-egress ports and the staggered relationship being such that the upper-wall portion of the bus-bar is substantially solid in the areas immediately above the said ingress-ports, thus causing air entering the former to wipe laterally across the interior surface of the rectangular bus-bar before exit through air-egress ports.

2. A bus-bar system comprising a plurality of one-piece wrought tubular bus-bars and composed of high electro-conductive metal and of rectangular form in cross-section and having substantially-flat integral top-, bottom- and side-walls; the said rectangular bus-bars being formed in a lower wall-portion with a longitudinal series of spaced-apart air-ingress ports, and also formed in an upper wall-portion with a longitudinal series of spaced-apart air-egress ports, the individual air-ingress ports being separated from others of the series thereof by webs of metal formed integrally with the metal of the rectangular bus-bar, and the individual air-egress ports of the series thereof being also separated from companion ports by integral webs; certain of the said ports being located laterally intermediate the longitudinal center-line of the upper-wall portion of the bus-bar and a side-edge of such wall portion and staggered relative to others of said ports in directions both laterally and longitudinally of the bus-bar and the staggered relationship being such that the upper-wall portion of the bus-bar is substantially solid in the areas immediately above the said ingress-ports, thus causing air entering ingress ports to travel both laterally and longitudinally through the interior of the rectangular bus-bar and exit through air-egress ports.

RICHARD W. SHOEMAKER.
